UNITED STATES PATENT OFFICE

2,479,064

MULTIFREQUENCY TUNING SYSTEM

Oliver W. Greene, Jr., Wakefield, R. I., assignor
to Greene Plastics, Inc., a corporation of Rhode
Island

Application April 21, 1947, Serial No. 742,888

3 Claims. (Cl. 250—40)

1

This invention relates to a multi-frequency tuning system and more particularly to a radio-frequency amplifier tank circuit with a switching means to change the band of operation and at the same time provide for the proper L-C ratio for load impedance for each band of operation.

In the prior art, several inductance elements have been provided to be selectively connected across a single variable capacitance. However, this arrangement has several disadvantages among which is the fact that the total capacitance is not normally used at the higher frequencies of operation, thereby limiting the dial rotation of the variable condenser and, in consequence, the band spread of the tuned circuit. Also, in the plug-in type of coil, a contact resistance is present in the circuit which may severely impede the efficiency of operation in a radio-frequency amplifier. Also, in a parallel L-C tank circuit, there are present high circulating radio-frequency currents; and, in prior arrangements, it is noted that this circulating radio-frequency circuit is broken each time a new frequency of operation is selected.

One of the objects of this invention is to eliminate the breaking of any contact where there is present a high radio-frequency current.

Another object of this invention is to eliminate the breaking of any circuit where there is present a high radio-frequency current by providing a permanent tank circuit with soldered low resistance connections.

Another object of this invention is to provide an individual tank circuit of the proper load impedance and L-C ratio for each band of operation and secondarily to provide complete band spread of 180° of operation of the condenser in the tank circuit.

With these and other objects in view, the invention consists of certain novel features of construction as will be more fully described and particularly pointed out in the appended claims.

In the accompanying drawings:

Fig. 1 is a diagrammatic view of a circuit in which the invention is located;

Fig. 2 is an end view of inductance and capacitance unit of the invention;

Fig. 3 is an elevation thereof with parts broken away;

Fig. 4 is an elevation of a fragmental portion of contacts between the unit and the circuit in which it is located;

Fig. 5 is an elevational detail on a larger scale of a portion of the showing of Fig. 3.

It is well known in the art that besides serving

2

as means for transforming the actual load resistance to the required value of plate load impedance to the tube, the plate tank circuit also should suppress the harmonics present in the tube output as a result of the non-sinusoidal plate current. For satisfactory harmonic suppression a Q of twelve or more with the circuit fully loaded is desirable. A Q of this order also is helpful from the standpoint of securing adequate coupling to the load or antenna circuit. The proper Q can be obtained by a suitable relation of L-C ratio in relation to the optimum plate load resistance for the particular tube selected. For a class C amplifier, operated under optimum conditions, plate load impedance is approximately proportional to the ratio of D.-C. plate voltage to D.-C. plate current. For a given effective Q, the tank capacity required at a given frequency will be inversely proportional to the parallel resistance so that it will also be inversely proportional to the plate voltage divided by the plate current ratio.

To reduce energy loss in the tank circuit, the inherent Q of the coil and condenser should be high. Transmitting coils usually have Q's ranging from 100 to several hundred. The tank transfer efficiency generally is 90% or more. An unduly large L-C ratio is not advisable since it would result in a large circulating radio-frequency tank current and, hence, relatively large losses in the tank with consequent reduction in the power available for the load.

Referring to the drawings, I have shown, a double-tube, push-pull radio-frequency amplifier circuit embodying this invention. It should be understood that this push-pull circuit is shown for purposes of illustration only, and this invention may be utilized in a single-tube radio-frequency amplifier circuit. The tank circuits which are particularly the subject matter of this invention are enclosed in dotted lines, being designated generally 15 and 25. Each of the tank circuits may be removed from the amplifier circuit as a whole by breaking the connection at the points T1, T2, T3, T4 and T5 in the tank circuit 15 or T6, T7, T8, T9 and T10 in the tank circuit 25. A tank circuit for a different operating band may be substituted therefor.

For example, in tank circuit 15, high radio-frequency circulating currents will be present 50 through inductance L_p and capacitances C1 and C2 completed from stator plates 10 and 11 through permanently connected leads 12 and 13. When changing the bands, the only interruption of this high radio-frequency current circuit is through the dielectric air gap of condensers C1 and C2.

Likewise, in tank circuit 25, high frequency alternating currents will be present through inductances L_g and capacitances C3 and C4 completed from stator plates 20 and 21 through permanently connected leads 22 and 23. The plate 5 voltage will be shut off when changing bands of frequency.

The tank changing mechanism is shown in Figs. 2 and 3 where a suitable base is designated 30 from which there extend upwardly standards 31 and 32 to rotatably support a shaft 33 in bearings at the upper ends of these standards. Upon this shaft, there is fixedly mounted a hub 34 which has a plurality of radiating arms 35 each of which supports an inductor 36 and the stator 15 of a capacitor 37 which consists of a plurality of plates 38. These plates 38 are electrically connected together by means of a bar which, in turn, is connected to the inductance coil.

The plates 38 are in two sections, one section being connected to one end of the inductance coil as at 40 and the other section being connected to the opposite end of the inductance coil as at 41. The inductor 36 is also formed in two sections, the inner ends of the two sections being suitably connected together. A link coil 42 or 43 is positioned between the two sections. A bar 45 of insulating material carries five contacts T1, T2, T3, T4 and T5 which are connected to the inductor and capacitor of the tank circuit as shown in the diagrammatic view in Fig. 1. The contacts T1 and T2 have wiping engagement with the spring arms 46, 47 which are connected to the tube plates, contact T3 which leads to the mid connector of the two inductor sections wipes arm 48 which is connected to the high voltage supply, and contacts T4 and T5 run to the ends of the link 42 and engage contacts 49, 49' which are connected to the antenna. This latter group is mounted on an insulating block held stationary or in a fixed position so that the contacts T3, T4 and T5 will wipingly engage these resilient arms as the tank is rotated into position. The tank 15 is connected in the same manner as the tank 15 above described.

The rotor of the capacitor, indicated diagrammatically at C1 and C2 (see Fig. 1), comprises a shaft 50 (see Fig. 3) which is rotatably mounted in bearings 50' on the standards or supports 31 and 32 which shaft carries the plates 51 which are fixed thereto to rotate therewith. These plates are provided in two groups, one group to interleave with one group of plates, while the other group of plates is positioned to interleave with the other group of plates. A suitable knob 54 is provided on the panel for rotating these plates so that tuning may be had within the band spread provided by the tank circuit above described.

Upon each of the radial arms 35, there will be mounted an inductor 36 and a capacitor stator 31 which together form a unit for a particular band spread. I have illustrated five such tanks which for the amateur range may be in frequencies of 10, 15, 20, 40 and 80. Each inductor and capacitor 36 and 37 will be so adjusted to provide the proper L-C ratio which will be most efficient for operation of this band spread. But one of these units, however, will be utilized at one time, and in order that one may be substituted for another,

I may merely rotate the shaft 33 so as to position the desired unit in operating relation with the rotor of the capacitor consisting of the plates 51 on the shaft 50; and, when in such a position that the stator plates of the capacitor interleave with the rotor plates of the capacitor, tuning in the band range may be had by rotation of the shaft 50 from the knob 54 on the panel.

In order to easily rotate the shaft 33, I have provided a gear 55 which is fixed on the shaft and which meshes with a small gear 56 on shaft 57 which has a crank 58 with handle 59; so that, as this crank is rotated, the shaft 33 will be rotated for suitably positioning the desired unit so that the stator will be in interleaving relation with the rotor. In order to register each unit in position, I have provided a spring pin 60 to extend into a suitable recess in the gear 55. A spring 61 forces this pin outwardly; but, as it has a rounded nose, an increased force will dislodge it from position for further movement of the gear.

I claim:

1. A multi range tuning device comprising a base plate, two inverted V-shaped members mounted a fixed distance apart on said base plate, two bearings affixed to the apex of said V-shaped members, a first assembly comprising a first shaft mounted in said bearings, a plurality of center tapped inductances mounted radially about said shaft on an axis parallel to the axis of said shaft and at an equal distance thereto, a plurality of mounting strips substantially the length of said inductances having perpendicularly mounted thereon and at each end thereof a group of spaced stator plates, each mounting strip being positioned on the periphery of each inductance and on an axis parallel to said shaft, each respective group of said stator plates being electrically connected together and to a separate end of each 35 of said inductances, a second assembly comprising a second shaft rotatably mounted within the area bounded by said base plate and the inverted V-shaped members on adjacent legs of said V-members and on an axis parallel to said first shaft, two groups of spaced rotor plates mechanically and electrically affixed perpendicularly on said second shaft and so positioned on said shaft so as to mesh with said stator plates when the first assembly is rotated into position 50 with said second assembly thereby forming a tuned circuit.

2. A device as claimed in claim 1, wherein there are four assemblies of center tapped inductances and stator plates arranged around said first shaft.

3. A device as claimed in claim 1, wherein there are a plurality of five prong plugs physically associated with each of said inductances and stator plates, to provide an electrical connection 60 to external circuits.
